UNITED STATES PATENT OFFICE

WILLIAM H. MUZZY, OF DAYTON, OHIO, ASSIGNOR TO THE NATIONAL CASH REGISTER COMPANY, OF DAYTON, OHIO, A CORPORATION OF OHIO, (INCORPORATED IN 1906.)

CASH-REGISTER.

1,026,763.

Specification of Letters Patent.

Patented May 21, 1912.

Application filed May 25, 1907. Serial No. 375,665.

To all whom it may concern:

Be it known that I, WILLIAM H. MUZZY, a citizen of the United States, residing at Dayton, in the county of Montgomery and 5 State of Ohio, have invented certain new and useful Improvements in Cash-Registers, of which I declare the following to be a full, clear, and exact description.

This invention relates to improvements in 10 cash registers, and has more particular relation to improvements in registers in which the cash of the several clerks is kept in separate receptacles or compartments, so that any errors or mistakes in making change, or in 15 depositing the money received, can be traced to the clerk making such mistake.

The object of the invention is to provide 20 improved means whereby the particular operated clerk's element of the machine must correspond to the cash receptacle opened, or otherwise such misoperation is at once apparent to the proprietor and the remaining clerks.

Another object of the invention is to provide 25 an improved alarm mechanism which will be put in operation upon the initial operation of the machine, and will not be put out of operation until all the different corresponding elements of the machine have 30 been properly operated.

With these and incidental objects in view, the invention consists in certain novel features of construction and combinations of parts, the essential elements of which are 35 set forth in appended claims and a preferred form of embodiment of which is hereinafter specifically described with reference to the drawings which accompany and form part of this specification.

10 Of said drawings: Figure 1 represents a transverse section through a machine of the type shown in the patent to Cleal and Reinhard No. 580,378, issued April 13, 1897, with my improvements applied thereto; the top 45 of the frame and a portion of the cash drawer casing being broken away. Fig. 2 represents a detail side elevation of the operating handle and driving gear, together with the machine lock; and Fig. 3 represents 50 a diagram of the wiring and the different circuits, including the main circuit breaker, connected to the rotation shaft of the machine.

In machines at present on the market, it 55 is customary to provide a series of clerks'

keys which, when depressed, determine the indicator to be set, the type character to be printed, and unlock the machine. These keys, which are termed the clerks' keys, also control the opening of the different cash receptacles or drawers; these drawers being opened upon the regular operation of the machine and according to the key depressed.

In the present invention there is no mechanical connection whatever between the clerks' keys or setting elements and the different cash drawers or receptacles, and either one or the other may be operated without operating the other. The electrical alarms, however, are so arranged that when a certain clerk's key is depressed, the A key for instance, an alarm will start to ring and will continue to ring until the machine is operated.

Further, the alarms are so arranged that should a cash drawer be first opened, an alarm will be set in operation and will continue in operation until the corresponding clerk's key is depressed and the machine operated.

If a clerk's key is first depressed and the wrong cash drawer opened, and the machine operated, the alarm will continue to ring and will be an indication to the proprietor and remaining clerks that the machine has been improperly operated.

Further, the tones of the alarm bells being different, will indicate to the several clerks just which cash receptacle has been improperly opened.

The keys 1 are arranged to be latched in their depressed position by a detent 2 pivoted upon a shaft 3. A lug 4 projecting laterally from the detent 2 engages an incline portion 5 of a pawl 6 secured to a transverse shaft 7, and rocks said shaft whenever the detent is oscillated by the depression of any one of the keys 1. The shaft 7 extends through the machine and has secured to its other end a locking pawl 8, the outer end of which is drawn into engagement with a shoulder 9 of a cut out portion 10 of a disk 11 by a spring 11a. This disk is secured to the side of a gear 12 which is driven in the direction of the arrow, Fig. 2, by a gear 13, which meshes with the gear 12 and also with a pinion 14 secured to the operating handle 15. A gear 16 secured to one end of a transverse shaft 17, meshes with the aforementioned gear 12.

It will be seen from the foregoing description that the operating handle is normally

locked and is only released upon the operation of one of the keys 1.

Each of the keys 1 has a laterally projecting pin 18, which when the key is depressed engages a pawl 19 pivoted to an arm 20, which in turn is pivoted to the frame of the machine, as at 21, and forces said arm downwardly against the tension of its spring 22. The inner end of each arm is normally in engagement with a contact plate 23 secured to the machine frame 24; each of the arms 20 and the contact plate 23 being suitably insulated from said frame. When the inner end of one of the arms 20 is forced downwardly by the depression of its key, it is carried out of engagement with the contact plate 23 and into engagement with a similar contact plate 25 also suitably mounted upon the frame of the machine. It is to be understood that for every key 1 there is an arm 20 and for every arm 20 there are contact plates 23 and 25. Adjacent to each of the arms 20 is an electromagnet 25^a, the purpose of which will be hereinafter described. The pawls 19 pivoted to the arms 20 are prevented from turning by pins 26 when the key pins 18 are depressed, but are free to rock about their pivotal points against the tension of light springs 27 when the key pins are returned to their normal outward position.

Each of the cash drawers 28, of which there are to be as many as there are clerks' keys 1, is provided with a pull 29 which covers the outer end of a latch 30 pivotally mounted within an opening 31 formed in the front partition of each cash drawer. The upper end of the latch 30 is forced into a recess 32 of a partition 32^a by a leaf spring 33, thereby preventing the accidental opening of the cash drawer.

To the rear end of each cash drawer is fastened an L shaped arm 34, the rear end of which is of insulating material. This insulated portion, when the cash drawer is closed, is arranged to spread apart two contact plates 35 and 36 which are mounted upon an insulated block 37 secured to the partition 32^a. Also mounted in the rear of each cash drawer 28 is a contact block 38, a magnet 39, pivotally mounted armature 40 and an electromagnetic bell 41, the purpose of which will be hereinafter explained.

Secured to the shaft 17, see Fig. 1, is a disk 42 equipped with a notch 43 which permits the spreading apart of the contact plates 44 and 45 once upon each revolution of the disk 42. The contact plates 44 and 45 are mounted upon an insulated block 46 suitably secured to the machine frame.

Referring to Fig. 3, the different circuits and methods of operation will now be described. Assuming that the clerk to whom the upper key and cash drawer are assigned has made a sale, he goes to the ma-

chine and depresses the keys representing the amount of the purchase and his initial key; the operation of the latter key by its pin 18 will force the arm 20 out of engagement with the contact plate 23 and into contact with the plate 25, thereby ringing the bell 41 located in the rear of the upper cash drawer by forming the following circuit: from the battery 51 to wire 50, contacts 44 and 45, wire 49, upper magnet 25^a, wire 47, contact 25, switch arm 20, wire 54, upper bell 41, wire 53, magnet 39, and over wire 52 back to the battery. The arm 20 carries an armature 20^a which holds the inner end of the arm in contact with the plate 25 as long as the magnet 25^a is energized, regardless of the position of the key pin 18. The next thing for the clerk to do is to open his cash receptacle, deposit the amount of the sale, close the cash drawer and then turn the handle 15. Near the end of the revolution of the disk 42 secured to the shaft 17, the cut away portion 43 of said disk will allow the temporary spreading apart of the contact plates 44 and 45, which will deenergize the magnet 25^a allowing the spring 22 to force the arm 20 out of contact with the plate 25 and thereby break the bell ringing circuit. The inner end of each of the arms 20 is flexible, so that there will be a slight give to said arm after it has been brought into contact with the plate 25 and before the pin 18 has passed the pawl 19; this is to compensate for any wear upon said pawl or pin and thus insure a perfect contact.

If the cash drawer is opened and closed before its companion key is depressed, the circuit is made as follows: from the battery 51 over wire 57 to the contacts 36 and 35, wire 55, contact plate 23, arm 20, wire 54, bell 41, wire 53, magnet 39 and by wire 52 back to the battery. When the magnet 39 is energized, it attracts the armature 40 against the tension of its spring 40^a, so that the inner end of said armature will engage with the contact block 38 and form the following shunt circuit when the drawer is closed: from the battery 51 over wire 57 to armature 40, contact block 38, wire 58, wire 55, and thence back to the battery over the circuit last described. Now upon operating the clerk's key corresponding to the cash drawer that has been opened and closed, it will be seen that the drawer circuit will be broken by the key pin 18 forcing the arm 20 out of engagement with the plate 23, and at the same time form the key circuit by carrying the arm 20 into engagement with the plate 25. This latter circuit is broken upon the operation of the machine as previously described. In order that the wiring forming the circuits for the second and third drawers, and their corresponding keys, may be readily traced, the same numerals are used, with the addition of the exponents

"b" and "c" respectively, as were utilized in describing the circuits for the first drawer and key.

It will be seen from the foregoing description that there are several methods or modes of operation, all of which are proper in the operation of this particular machine. First, press the proper clerk's key; second, open the cash drawer, make the change and close the drawer again, and third, operate the machine. The second means of operation is, to first open and shut the cash drawer, next press the clerk's key and finally operate the machine. When there is a charge transaction, or any other transaction not requiring the opening of the cash drawer, the clerk's key is first depressed and the handle then operated; no cash drawer being opened at all. In any selected mode of operation, the turning of the crank handle is the last operation of the machine; and if a cash drawer is opened after this turning of the handle, an alarm will always be set in operation and will not be again arrested until the proper clerk's key is operated and the machine handle turned.

The invention provides means whereby the operator may suit his own convenience in the method of operation of the machine. If desired, he may first open the cash drawer, make change and then close the drawer. This will start a particular alarm, and unless he operates the corresponding clerk's key the alarm will continue to sound. If he so desires, he can first operate the clerk's key, then open his cash drawer, make change and close the drawer, which will still leave the alarm ringing, and finally turn the handle to momentarily break the circuit. The operator is not compelled, in any of these operations, to follow any certain sequence of movement or to open a cash drawer corresponding to a clerk's key depressed; but if he does not properly operate the mechanism as above described, an alarm which has been set in operation to indicate which clerk is at the machine, will be left in operation and thus indicate to all concerned that the clerk at the machine has not properly operated it.

If a cash drawer has been opened not corresponding to the depressed key, the alarm can only be stopped by the clerk operating the machine, and then depressing the key corresponding to the previously opened cash receptacle, and operating the machine a second time. By this method of manipulation the clerk is in great danger of being caught, as not only will the alarm announce that the clerk has opened the wrong drawer but the clerk's indicator will also disclose this fact to the other clerks and the customers in the store.

The clerks' keys beginning at the top of the bank, correspond to the cash receptacles

similarly located within the cabinet. As the invention is shown the clerks' keys perform the function of releasing the operating mechanism, and controlling alarm devices only, but it will be readily understood that in practice these keys are also used to determine the setting of an indicator and a printing device to selected positions, as described in the cited patent. These keys, therefore, perform the function of selecting the proper alarm device and other parts of the mechanism for operation, and it is to be understood that the invention contemplates the use of any form of manipulative devices which have a selective action such as outlined.

While the form of mechanism here shown and described, is admirably adapted to fulfil the objects primarily stated, it is to be understood that it is not intended to confine the invention to the one form of embodiment herein disclosed, for it is susceptible of embodiment in various forms all coming within the scope of the claims which follow.

Having thus described my invention, what I claim as new and desire to secure by Letters Patent is:

1. In a machine of the class described, the combination with an operating mechanism, of selective devices, a series of clerks' cash receptacles, a series of signals, means controlled by the selective devices or the cash receptacles for starting the signals, and means requiring an operation of the operating mechanism for arresting said signals. 100

2. The combination with an operating mechanism, of clerks' selective devices, a series of cash receptacles, a series of alarms, one for each receptacle, means controlled by any of the receptacles for starting its alarm, 105 and means controlled by the operating mechanism and the selective device corresponding to the receptacle operated for arresting the alarm.

3. The combination with an operating mechanism, of a series of clerks' keys, a series of cash receptacles, alarms, and connections whereby the operation of a clerk's key or the opening of a cash receptacle will put one of the alarms in operation, with provisions whereby such alarm will be arrested by the operation of the corresponding clerk's key or cash receptacle and the movement of the operating mechanism. 115

4. In a machine of the class described, the combination with a main operating mechanism for the machine, of a clerk's key, a cash receptacle, an alarm, a circuit for said alarm, and circuit breakers for said alarm circuit controlled respectively by said operating mechanism, said key and said cash receptacle. 125

5. In a machine of the class described, the combination with a series of clerks' keys, a series of cash receptacles, a series of alarms, 130

- and connections whereby the alarms are operated upon either the operation of a clerk's key or the opening of a cash receptacle.
5. 6. In a machine of the class described, the combination with an operating mechanism, of a series of clerks' keys, a series of cash receptacles, a series of alarms and connections, and means for controlling the alarms from the clerks' keys, the cash receptacles and the operating mechanism.
10. 7. In a machine of the class described, the combination with a main operating mechanism for the machine, of a clerk's selecting device, a cash receptacle, means for announcing the initial opening of the receptacle, devices, actuated by operation of the clerk's selecting device and the operating mechanism, for discontinuing the operation of said announcing means, connections, controlled by initial operation of the selecting device, for operating said announcing means, said devices actuated by the operating mechanism serving alone to cause discontinuance of the operation of said announcing means by said selecting device connections.
15. 8. In a machine of the class described, the combination with an operating mechanism, of a lock for the same, clerks' setting elements controlling the lock, a series of cash receptacles, and alarms set in operation by either the cash receptacles or the clerks' setting elements.
20. 9. In a machine of the class described, the combination with an operating mechanism, of a series of cash receptacles, a series of alarms set in operation by the opening of the receptacles, and mechanism compelling an operation of the operating mechanism to arrest the alarms.
25. 10. In a machine of the class described, the combination with a plurality of cash receptacles, of selective devices, a series of alarms, an operating mechanism, means for operating the alarms by the movement of the cash receptacles or the selective devices, and means for arresting the alarms upon the movement of the operating mechanism.
30. 11. In a machine of the class described, the combination with a plurality of cash receptacles, of selective devices, a series of alarms, means for operating the alarms by the movement of the cash receptacles or the selective devices, an operating mechanism, a lock for said mechanism under the control of the selective devices, and means under control of the operating mechanism for arresting the alarms.
35. 12. In a machine of the class described, the combination with a series of alarms, of a plurality of independent groups of manipulative devices for operating said alarms, and means under control of one group of manipulative devices for arresting the alarms after being put into operation by the other group.
40. 13. In a machine of the class described requiring a manipulation of different devices for a complete operation of the machine, an alarm, means for operating said alarm upon the operation of a part of said devices, and means for arresting the alarm upon the operation of all of the devices.
45. 14. In a machine of the class described, the combination with a series of alarms, of a series of setting elements, a series of cash receptacles, and electrical means for operating the alarms upon the movement of the setting elements or the cash receptacles.
50. 15. In a machine of the class described, the combination with a series of alarms, of a series of setting elements, a series of cash receptacles, and independent alarm ringing circuits under the control of the setting elements and the cash receptacles.
55. 16. In a machine of the class described, the combination with a series of keys, of a series of cash receptacles corresponding thereto, a series of alarms, and independent ringing circuits for each alarm under the control of one of the keys and its corresponding cash receptacle.
60. 17. In a machine of the class described, the combination with a series of alarms, of a series of setting elements, a series of cash receptacles, independent alarm ringing circuits under the control of the setting elements and the cash receptacles, and means under the control of the setting elements for cutting out the receptacle circuit.
65. 18. In a machine of the class described, the combination with a series of setting elements, and an alarm for each element, of electrical connections whereby actuation of any setting element operates the corresponding alarm, and an operating mechanism for arresting the operated alarm irrespective of the position of the setting element.
70. 19. In a machine of the class described, the combination with a series of alarms, of a series of setting elements, a series of cash receptacles, an operating mechanism, an alarm ringing circuit under the control of the cash receptacles, means under control of the setting elements for breaking the receptacle circuit and making a setting element circuit, and means under the control of the operating mechanism for breaking the setting element circuit.
75. 20. In a machine of the class described, the combination with a clerk's setting mechanism, of a series of corresponding cash receptacles, a series of alarms and connections, with provisions whereby any alarm set in operation will continue in operation when non-corresponding clerks' selective devices and cash receptacles are operated.
80. 21. In a cash register, the combination

with a clock's selective device, of an operating mechanism, a signal, means controlled by the selective device for starting the signal, and separate and independent means controlled by the operating mechanism for arresting said signal.

22. The combination with an operating mechanism, of a manipulative device, a second manipulative device, an alarm, means controlled by either manipulative device for starting the alarm, means controlled by the operating mechanism alone for arresting the alarm when one of said devices is operated, and means requiring the operation of both the remaining manipulative device and the operating mechanism to arrest the alarm when the other manipulative device is operated.

23. In a cash register, the combination with a series of manipulative devices, of a corresponding series of cash receptacles, a series of alarms, means for sounding one of said alarms when corresponding selective devices and receptacles are operated, and means for sounding a plurality of alarms when non-corresponding selective devices and receptacles are operated.

24. In a machine of the class described, the combination with parts designed to be manually actuated in a predetermined sequence, of an alarm, means for temporarily operating said alarm when said predetermined sequence is observed, and means for prolonging the operation of said alarm if said parts are operated in other than said predetermined sequence.

25. In a machine of the class described, the combination with parts designed to be manually actuated in a predetermined sequence, of a signal, means for actuating said signal in one manner when said predetermined sequence is observed, and means for actuating said signal differently if a sequence of operation other than that predetermined is followed.

26. In a machine of the class described, the combination with a key and an alarm device, of a circuit for said alarm device closed by said key, means for retaining the circuit closed irrespective of the key, and a main operating mechanism for the machine having connections for finally breaking said circuit.

27. In a machine of the class described,

the combination with a key and an alarm device, of a circuit including said alarm device and controlled by said key, means for maintaining the electrical condition of the circuit irrespective of the key, and a main operating mechanism having connections for finally reversing the electrical condition of the circuit.

28. In a machine of the class described, the combination with a key, and an alarm device, of a circuit including said alarm device and constructed to have its electrical condition changed by the key, means for maintaining the changed condition of the circuit irrespective of the key, and a main operating mechanism, having connections for restoring the original electrical condition of the circuit.

29. In a machine of the class described, the combination with a cash receptacle, and an alarm device, of a circuit including said alarm device constructed to be closed by said receptacle, means including a shunt for maintaining said circuit closed, and a main operating mechanism having connections for finally opening said circuit.

30. In a machine of the class described, the combination with a key and a cash receptacle, of a single alarm device, circuits for said device constructed to be closed respectively by said key and receptacle, means for maintaining said circuits closed irrespective of said key and receptacle, and a main operating mechanism having connections for finally opening said circuits.

31. In a machine of the class described, the combination with a key and a cash receptacle, of a single alarm device, circuits for said alarm device constructed to be closed by said key and said receptacle, and a main operating mechanism having connections for opening said circuits.

32. In a machine of the class described, the combination with registering mechanism, of a cash drawer, an alarm set in operation by movement of the cash drawer, and means operative with the registering mechanism for arresting the alarm.

In testimony whereof I affix my signature in the presence of two witnesses.
